UNITED STATES PATENT OFFICE.

JOHN S. DEAL, OF MONROE, WISCONSIN.

STIRRING APPARATUS.

SPECIFICATION forming part of Letters Patent No. 772,701, dated October 18, 1904.

Application filed February 15, 1904. Serial No. 193,650. (No model.)

To all whom it may concern:

Be it known that I, JOHN S. DEAL, a citizen of the United States, and a resident of Monroe, in the county of Green and State of Wisconsin, have invented a new and Improved Stirring Apparatus, of which the following is a full, clear, and exact description.

The invention relates to apparatus used in the manufacture of cheese; and its object is to provide a new and improved stirring apparatus more especially designed for stirring milk in the cheese-kettle and arranged to allow of moving the kettle over or off the fire without interruption of the stirring process.

15 The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in both views.

Figure 1 is a perspective view of the improvement, part of the kettle being broken out; and Fig. 2 is a plan view of the same, the kettle and stirrer being omitted.

The kettle A is hung on the horizontal member B' of a crane B of any approved construction, having its vertical member B² journaled in suitable bearings arranged in the building in which the apparatus is located. Into the kettle A extends the usual stirrer C, having its shaft C' journaled at the upper end in suitable bearings in the horizontal member B' of the crane, so that when the shaft is turned the stirrer C is caused to swing around in the kettle to agitate the material contained therein.

On the upper end of the shaft C' is secured 40 a sprocket-wheel D, connected by a sprocket-chain D' with a sprocket-wheel D², attached to a vertical shaft E, journaled in suitable bearings carried by the crane B. On the shaft E is also secured a bevel gear-wheel F, 45 in mesh with a bevel gear-wheel F', secured at one end of a horizontally-disposed shaft F², journaled adjacent to the bevel gear-wheel F' in a suitable bearing G, mounted to swing loosely on the shaft E. The other end of the

shaft F' is mounted to slide in and to turn 50 with a sleeve H, connected by a universal joint I with one end of a counter-shaft J, journaled in suitable bearings attached to supports in the building, and on the said counter-shaft J are secured fast and loose pulleys 55 K, connected by belt with other machinery. The counter-shaft and pulleys, as illustrated, are stationary relatively to the kettle and stirrer, which have the independent swinging movement of translation previously described. 60

When the counter-shaft J is rotated, the universal joint I imparts a rotary motion to the sleeve H, which in turn rotates the shaft F², so that the gear-wheels F' and F rotate the vertical shaft E, and the latter, by the 65 sprocket-wheels D² and D and the sprocket-chain D', imparts a rotary motion to the stirrer-shaft C' to move the stirrer C around in the kettle A.

By having the kettle mounted on the crane 70 B it is evident that the kettle can be swung over the fire for heating the kettle and its contents, and when desired the kettle can be swung off the fire by turning the crane B correspondingly; but in either of the two positions of the kettle the stirrer C can be kept revolving within the kettle, owing to the gearing described, as the bearing G, shaft F', sleeve H, and universal joint I allow a swinging motion of the crane B without causing 80 cessation of the rotation of the shaft C' as long as the counter-shaft J is kept in motion.

It is understood that when the crane B is swung from one position to the other the shaft F' slides in the sleeve H, but is still turned 85 by the latter, and the bearing G swings freely on the shaft E, so as to keep the gear-wheels F' and F in mesh and the shaft F² in proper alignment with the sleeve H without binding.

The device is very simple and durable in 90 construction, can be cheaply manufactured, and is arranged to allow of moving the kettle onto or off the fire without interruption of the stirring.

Having thus described my invention, I claim 95 as new and desire to secure by Letters Patent—

1. The combination with a kettle, of a stirrer operating therein, a movable support for

the kettle, relatively stationary power mechanism, and a driving device connecting the power mechanism and stirrer.

2. The combination with a kettle, of a stirrer operating therein, a movable support for the kettle, relatively stationary power mechanism, and a driving device connecting the power mechanism and stirrer and including an extensible shaft.

3. The combination with a kettle, of a stirrer operating therein, a movable support for the kettle, relatively stationary power mechanism, and a driving device connecting the power mechanism and stirrer and including a universal joint.

4. A stirring apparatus comprising a kettle, a stirrer in the kettle, a swinging support for the kettle, to move the latter over or from the fire, and a driving device for driving the stirrer in the kettle, arranged to drive the stirrer in any position the kettle may be in, the said driving device consisting of a gearing on the said support, connected with the shaft of

the said stirrer, a counter-shaft, and a self-adjusting connection between the said counter-shaft and the said gearing, as set forth.

5. A stirring apparatus comprising a kettle, a stirrer in the kettle, a swinging support for the kettle, to move the latter over or from the fire, and a driving device for driving the stirrer in the kettle, arranged to drive the stirrer in any position the kettle may be in, the said driving device consisting of a gearing on the said support, connected with the shaft of the said stirrer, a counter-shaft, a sleeve mounted to slide on and to turn with the shaft of the said gearing and a universal joint connecting the said sleeve with the said counter-shaft, as set forth.

In testimony whereof I have signed my name to this specification in the presence of two subscribing witnesses.

JOHN S. DEAL.
